(57) **CLAIM**

The ornamental design for an edge clip, as shown and described.

DESCRIPTION

FIG. 1 is a perspective view of the edge clip of the new design;

FIG. 2 is a right side view thereof, the left side view being a mirror image thereof;

FIG. 3 is a front view thereof, the rear view being a mirror image thereof;

FIG. 4 is a top view thereof; and,

FIG. 5 is a bottom view thereof.

The features shown in broken lines depict portions of the edge clip that form no part of the claimed design.

1 Claim, 5 Drawing Sheets(56)
